UNITED STATES PATENT OFFICE.

SALE A. PICKENS, OF NEW YORK, N. Y.

AUTOMOBILE-DOOR.

1,223,903.

Specification of Letters Patent. Patented Apr. 24, 1917.

Application filed November 9, 1915. Serial No. 60,517.

To all whom it may concern:

Be it known that I, SALE A. PICKENS, a citizen of the United States, and a resident of the city of New York, borough of Manhattan, in the county and State of New York, have invented a new and Improved Automobile-Door, of which the following is a full, clear, and exact description.

Among the principal objects which the present invention has in view are: to provide means for deflecting the air through which an automobile may be passing through the body of the door thereof for creating a circulation of relatively cool air adjacent the floor of the automobile; to provide means for preventing the rattling of the air-circulating members when in closed position; to provide means for automatically increasing the intake of air proportionate to the increase of speed of the automobile and coincident with increase in heat below the floor of the automobile; and to simplify the mechanism and reduce the cost thereof.

Figures.

Figure 1 is an interior side view of an automobile door, showing in conjunction therewith an air-circulating device and mechanism for operating the same constructed and arranged in accordance with the present invention;

Fig. 2 is a detail view on an enlarged scale, in section, the section being taken as on the line 2—2 in Fig. 1;

Fig. 3 is a detail view on an enlarged scale, in section, the section being taken as on the line 3—3 in Fig. 1;

Fig. 4 is a similar view taken as on the line 4—4 in Fig. 1; and

Fig. 5 is a similar view taken as on the line 5—5 in Fig. 1.

Description.

Automobiles have heretofore been subject to the objection of excessive heat incident to the placement of the machinery under the floor of the automobile, whereby the heated products of combustion are conveyed to the rear of the machine to be there expelled. Where machines have been equipped with side doors, accumulation of heat in this manner has proved exceedingly uncomfortable for riders. Heretofore endeavor has been made to overcome the objection by introducing ventilating systems having air supplied from the front of the vehicle. This

has necessarily been limited, and in order to supply the necessary volume of air, the intake thereof has been necessarily forced. The result of this method of supplying air has been to introduce a relatively small stream of air into the body of the machine in a forceful manner.

In the present invention the air is introduced in larger volumes with less violence, and distributed by slower and more agreeable currents throughout the body of the machine, accomplishing the purpose desired without inconveniencing the passengers.

As seen in the drawings, a door 10 of conventional structure has formed therein a series of narrow vertical openings 11. The openings 11 are formed, in part, by intermediate rails 12, which form supports for certain of the doors or louvers 13. The louvers 13 are supported by hinges 14 upon the rails 12 and door 10. The free edges 15 of the louvers 13 are preferably rounded to set in grooved faces 16 of the rails 12.

Each of the various louvers 13 is held in position by a spring 17. One end of each spring 17 is secured to a bracket arm 18 on each of the louvers 13, and the other end to a corresponding bracket arm 19 mounted on a hollow master bar 20. The master bar 20, when moved to relax the tension on the springs, permits the louvers 13 to move outward from the door 10, drawn thereto by the air currents through which the machine or automobile passes. The springs 17 thereafter operate in correspondence with the air pressure. The air pressure on the louvers 13 usually corresponds with the speed of the machine, which, in turn, is correspondingly related to the heat produced by the engine. Therefore, the cooling effect of the circulating air introduced is automatically proportioned to the heat radiated from the engine under the body of the machine.

The master bar 20 is preferably semi-tubular in form for providing a housing for the springs 17 and the brackets 18 and 19 when the louvers 13 are closed. At one end, the bar 20 is provided with guide rod extensions 21. The extensions 21, as seen best in Fig. 2 of the drawings, pass through bearings formed in a guide bracket 22 securely mounted on the door 10. As shown in the drawings, at Figs. 1 and 3, two extensions 21 are employed for balancing the bar 20.

At the opposite end of the bar 20, a screw-

threaded extension 23 is engaged by a nut 24 and supported in bearings formed in brackets 25. Bearing against the adjacent faces of the brackets 25, the nut 24 is prevented from roving, with the effect that the extension 23 and master bar 20 connected therewith is moved in accordance with the manipulation of the nut 24.

When the bar 20 is retracted so that the 10 springs 17 exert a setting or closing pressure on the louvers 13, the tension of said springs is so imparted to the brackets 18, that the louvers are held firmly and snugly to their seats, the edges 15 resting firmly in the faces 15 provided to receive them.

It is obvious that when the louvers 13 are open, the pressure of the air and the counteracting influence of the springs 17 prevents any rattling of said louvers. It is 20 also obvious that when the louvers are closed, the pressure of the springs 17 is exerted thereon to hold the free edges of the louvers firmly in the faces 16.

It is also obvious that the pressure of the springs 17 is exerted on the nut 24, and that 25 in this manner there is avoided any objectionable rattling of the movable parts of the structure.

Claim.

An automobile door having a series of 30 elongated vertical openings; a series of solid louvers therefor each being pivotally connected at the rear edge of one of said openings; a master bar reciprocatively mounted transverse said openings; a series of springs 35 operatively connecting said master bar and each of said louvers; and means for manually adjusting said master bar, said means embodying a screw-threaded extension of said master bar, and a rotary nut operatively connected therewith.
